UNITED STATES PATENT OFFICE.

JOHN THIES AND FRANK THIES, OF HUTCHINSON, KANSAS.

LUG FOR TRACTOR WHEELS AND THE LIKE.

Application filed July 14, 1927. Serial No. 205,682.

This invention relates to a detachable lug for use on the wheels of tractors and the like, one of the objects being to provide a simple and efficient device of this character 5 which is reversible so that when the outer or working end of the lug becomes worn the device can be removed, reversed, and replaced, thereby doubling its life.

A further object is to provide a lug which 10 can be reversed for use when a wheel is to be rotated in either direction, the parts being so assembled that the lug can, if desired, be reversed without completely removing its attaching means.

15 With the foregoing and other objects in view which will appear as the description proceeds, the invention resides in the combination and arrangement of parts and in the details of construction hereinafter described 20 and claimed, it being understood that changes in the precise embodiment of the invention herein disclosed may be made within the scope of what is claimed, without departing from the spirit of the invention.

25 In the accompanying drawings, the preferred forms of the invention have been shown.

In said drawings,

30 Figure 1 is a side elevation of a portion of a wheel rim, part of said rim and the lug thereon being shown in section.

Figure 2 is a perspective view of the lug.

35 Figure 3 is a section through a portion of a wheel rim and a modified form of lug, an intermediate position of the lug during the reversing operation, being indicated by broken lines.

Figure 4 is a perspective view of the lug shown in Figure 3.

40 Referring to the figures by characters of reference 1 designates an arcuate plate the ends of which are preferably rounded off to transverse edges 2 while the sides of this plate are provided with parallel integral wings 3. A transverse web 4 is interposed 45 between and integral with the wing and radiates from the center of the convex face of plate 1, the outer or free edge 5 of this web being reduced, as shown, and constituting one of the bearing edges of the lug. An opening 6 is extended through the web close 50 to the plate 1 and in opposite faces of the web are provided recesses 7 constituting seats for a bolt head.

55 The free edges of the wings 5 are preferably slightly concaved in the direction of

their length so that when applied to the rim R of a wheel, they will conform with the curvature thereof and fit snugly thereagainst as shown particularly in Figure 1. The 60 wheel rim has an opening A for each lug and after the lug has been positioned properly adjacent the opening with one of the edges 2 bearing against the rim, a bolt 8 is inserted through the opening 6 and the rim 65 opening A until the head of the bolt rests in the outer recess 7. Said bolt is then tightened by means of a nut 9 and, if desired, an angular washer 10 can be interposed between the nut 9 and the inner surface of the rim R. This arrangement of 70 the parts has been illustrated in Figure 1.

By tightening the bolt the parts are obviously held together securely. Should the outer portion of the lug become worn the 75 same can easily be detached, reversed and resecured to the rim. By providing an opening A which is tapered as shown in Figure 1 the lug can be reversed so as to be effective when the wheel is revolved in the opposite 80 direction. Thus reversal can be effected simply by loosening the bolt, revolving the lug therearound so as to cause the bolt to swing to another angle, after which the bolt can be tightened, thus holding the lug in a position opposite to that illustrated in Figure 1 so that it will be effective when the wheel is rotated oppositely to the direction for which the parts are shown set in Figure 1.

Of course if it is not designed to utilize a 90 lug reversible for movement in either of two directions, it is not necessary to use a tapered opening A.

Another form of reversible lug has been illustrated in Figures 3 and 4. This lug 95 includes a casting having a concave working face 11 rounded at its ends to the edges 12. This lug is formed of a solid block having an angular recess 13 in its working face and a slot 14 opens into this recess across the 100 angle portion of the back of the lug. Recess 4 is designed to receive the head 15 of a bolt 16 and when the lug is arranged on the rim of a wheel as shown at R' this bolt can be used for binding the lug firmly against the 105 rim. For the purpose of reversing the position of the lug on the rim the bolt 16 is loosened sufficiently to allow the lug to rock or tilt from one position to another. An intermediate position assumed by the lug 110 during this operation has been indicated by broken lines in Figure 3. Both of the rim

engaging faces of the lug are recessed so as to fit snugly upon the wheel rim when clamped thereto.

What is claimed is:

5 A reversible lug for tractor wheels including an arcuate member having an outwardly extending active face, backwardly extending wings at the sides of said face, a transversely disposed central web between and integral with the wings, said web radiating

from the arcuate member and having an aperture, and means extending through said aperture for holding the outer edge of the web and either end of the active face of the lug against the rim of a wheel.

In testimony that we claim the foregoing as our own, we have hereto affixed our signatures.

JOHN THIES.
FRANK THIES.
